SUCTION CLEANER NOZZLE ADJUSTMENT
SIGNAL

Eugene F. Martinet, Cleveland, Ohio, assignor to
The P. A. Geier Company, Cleveland, Ohio, a
corporation of Ohio

Application September 8, 1937, Serial No. 162,908

6 Claims. (Cl. 15—9)

The invention relates to a portable suction cleaner, including a nozzle and associated means which are adjustable to vary the relative location of the nozzle mouth with respect to the particular surface being cleaned.

In a suction cleaner, whether or not a power driven rotary brush or agitator is provided in its nozzle mouth, substantially no cleaning takes place unless the nozzle mouth is properly located with respect to the particular surface to be cleaned, so as to provide the proper nozzle adjustment between the surface being cleaned and the nozzle mouth as the cleaner is moved across the surface being cleaned.

15 Rugs having different nap thicknesses, and floor surfaces of wood, linoleum, tile or the like, each require a different adjustment of the nozzle mouth with respect to the surface, to provide the proper nozzle adjustment for most effective cleaning.

Moreover, if the nozzle adjustment is too close to the surface being cleaned, the nozzle will tend to dig into the surface and it will be difficult or hard to push the cleaner back and forth across the surface, or in the case of a bare floor and the like, the cleaner nozzle may scrape the surface.

Thus, it is particularly important that the adjustment of the cleaner nozzle mouth with respect to the surface being cleaned, shall not be any closer than is necessary to provide a maximum amount of cleaning effect, with the least amount of effort on the part of the operator, and with a minimum of wear on the surface being cleaned.

I have heretofore provided signaling means for indicating when the proper nozzle adjustment has been effected in connection with the operation of manual adjusting means, as set forth in my copending applications, Serial Nos. 73,868 (Patent No. 2,120,011) and 78,624; and I have also provided means for automatically adjusting the nozzle mouth to that a maximum predetermined cleaning effect is produced, as set forth in my copending application, Serial No. 145,998; and such constructions are admirably satisfactory for the purposes intended. However, each of these prior constructions involve certain changes or additions in the usual construction of a suction cleaner; and are not readily adapted for being applied as attachment parts to cleaners which have been sold and are in use.

The objects of the present invention include 55 in general the provision of a very simplified con-

struction of signaling means which may be associated with the nozzle of a suction cleaner and operated by variations in the suction or pressure of the air in the nozzle to indicate to the user a desired particular condition of the suction air, such as when the suction or pressure in the nozzle is such as will provide a maximum amount of cleaning as when the nozzle has been properly adjusted.

A further object of the present invention is to provide a signaling device incorporated in a removable attachment which may be applied to an opening present or formed in a nozzle wall of a suction cleaner to indicate the attainment of a desired satisfactory condition of the suction air in the nozzle such as will provide a maximum amount of cleaning as when the nozzle has been properly adjusted.

A further object of the present invention is to provide a simple signaling device incorporated in an attachment which may be secured to the converter opening of sundry types, kinds, styles and makes of suction cleaners in place of the cover plate usually used to close the converter opening, for indicating the attainment of the proper nozzle adjustment to secure a maximum amount of cleaning.

The foregoing and other objects are attained by the suction cleaner, apparatus, parts, improvements, attachments, combinations, and sub-combinations, which comprise the present invention; the nature of the same being set forth in the following general statement and preferred embodiments of which, together with their mode of use, are set forth in the following description; and which are particularly and distinctly pointed out and set forth in the appended claims forming part hereof.

The nature of the improvements of the present invention may be described in general terms as including preferably in a portable suction cleaner, a suction nozzle communicating with ducts or passages, means for flowing suction cleaning air into the nozzle and through the ducts, preferably wheel supporting means associated with the nozzle, means for adjusting the wheel supporting means, and means associated with the nozzle actuated by variations in the suction or pressure existing in the nozzle or ducts for indicating to the user of the cleaner a particular condition of the suction air such as that when proper adjustment of the nozzle mouth has been effected for providing for a maximum cleaning action of the cleaner; said signaling means preferably comprising a device for re-

movable attachment to the converter opening of a suction cleaner.

By way of example, several embodiments of the present improvements are illustrated in the 5 accompanying drawings forming part hereof in which

Figure 1 is a perspective view of a suction cleaner equipped with the improved signaling device in the form of a removable attachment 10 adapted for being secured to the converter opening of the cleaner;

Fig. 2 is an enlarged side elevation, with portions broken away and in section, of an electrically operated portable suction cleaner provided with the signaling device shown in Fig. 1, and showing the relative positions of certain of the parts before proper nozzle adjustment has been effected;

Fig. 3 is a longitudinal section through the 20 improved signaling device shown in Fig. 2, with the parts thereof in the relative positions associated with the relative positions of the parts of the cleaner shown in Fig. 2;

Fig. 4 is a view similar to Fig. 2, but showing 25 the relative positions of certain of the parts of the cleaner after the nozzle has been adjusted to locate the nozzle mouth at the proper position to obtain maximum cleaning action for the particular nap rug illustrated;

Fig. 5 is a view similar to Fig. 3, but showing 30 the parts of the signaling device in their relative positions associated with the relative positions of the cleaner parts shown in Fig. 4;

Fig. 6 is a front elevation of the signaling attachment shown in Fig. 5;

Fig. 7 is a rear view of the signaling attachment shown in Fig. 5; and

Figs. 8 and 9 are views similar to Figs. 3 and 5 of a modified form of construction.

Similar numerals refer to similar parts throughout the several figures of the drawings.

An electrically operated portable suction cleaner with a power driven rotary brush in the nozzle chamber thereof and with a headlight, and provided with one embodiment of the present improvements, is shown in Figs. 1 to 7, inclusive, and is generally indicated at 10.

The suction cleaner 10 includes a motor (not shown) in a motor housing 11, associated with a 50 fan housing 12 having a fan 13 therein secured on the motor shaft, and a suction nozzle 14 is located adjacent to and communicates with the fan housing. An operating handle 15, and a dust bag 16 connected with the exhaust opening of the 55 fan housing 12 are also provided for the cleaner; and the motor housing 11, the fan housing 12, and nozzle 14 are mounted on front casters 17 and preferably on adjustable double rear caster means 18 for ambulant motion over a surface to be 60 cleaned, the surface being a nap rug 19 in Figs. 2 and 4. The cleaner 10 is also provided with headlight means indicated generally at 20.

The suction nozzle 14 preferably includes walls forming a tubular neck 21 leading to the fan 65 chamber 12, and a transversely elongated brush housing mouth 22 terminating in lip walls 23a and 23b.

A rotary brush generally indicated at 24, and provided with bristles 25 is preferably detachably 70 and adjustably rotatably mounted in the suction mouth 22, and the brush 24 is preferably motor driven, as shown in the drawings, preferably by an endless flat band rubber belt 26, which passes over the brush pulley surface 27 and the pulley 75 surface 28 of motor shaft extension 29.

As shown, the lip walls 23a and 23b of the nozzle are preferably provided at the entrance to the nozzle mouth 22 with a nozzle lip plate and brush guard 30.

The headlight means generally indicated at 20, 5 as shown, includes an upper centrally located forwardly opening headlight shield 31 within the chamber 32 of which is operatively mounted an electric headlight bulb 33, which is associated with a source of power for the motor, the headlight 10 33 being preferably lighted when the motor and fan are in operation.

The front wheel or caster supporting means indicated generally at 17, preferably include front axles 34 extending respectively coaxially and laterally outward on opposite sides of the lower 15 portions of the fan housing; and the wheels 17 are journaled on said front axles 34.

The adjustable double rear caster means generally indicated at 18, preferably include a bracket 20 member 35 secured to the motor housing 11 to which is pivotally mounted the frame member 36, on which the wheels 18 are journaled at 37. An adjusting screw 38 is threaded into an extension 39 on the motor housing 11 to press against frame 25 member 36, which is normally urged toward the end of the screw 38 by spring 40.

In the style of cleaner shown in the drawings, the front wall of nozzle 14 is provided with an auxiliary opening 41 through which a converter 30 attachment may be passed for connecting a flexible hose to the fan chamber of the cleaner 10. Normally, the converter attachment opening 41 is closed with a disk plate, which sometimes forms the name plate for the cleaner, and for the purposes of the present invention, the improved signaling device generally indicated at 42 is substituted for the usual converter opening closure plate.

Referring to Figs. 3, 5, 6 and 7, the signaling 40 device preferably includes a concaved front plate 43 terminating at 44 in an annular flange and provided with a central opening 45, a handle knob 46, and two or more apertures 47. The signaling device also includes a rear plate 48, to which a 45 strip spring clip 49 is secured at 50 for removably securing the attachment 42 to the cleaner converter opening 41, as shown in Figs. 2 and 4. Two or more openings 51 are also provided in the rear plate 48.

The front and rear plates 43 and 48 form a chamber indicated at 52 in which is located a rubber disk diaphragm 53, the peripheral edge 54 of which is tightly clamped between plates 43 and 48 when assembling plates 43 and 48 together as 55 by beading or peening over the end of the annular flange 44, as indicated at 55. The rubber diaphragm 53 has a button 56 secured to the central portion thereof, as by providing washers 57, by forming a central aperture in the diaphragm, by 60 passing the inner end of the button 56 through the washers and diaphragm aperture, and by securing the washers 57 to the reduced neck 58 on the inner end of the button 56 to clamp the diaphragm between the washers 57.

A spring 59, engaged over a central pin 60 on the inner side of plate 48, and engaged in a recess 61 within button 56, normally urges the button outward through the central aperture 45 of the front plate 43, so that the various parts of the 70 signaling device 42 normally assume the positions shown in Fig. 3.

The apertures 47 in front plate 43 permit atmospheric pressure to reach the diaphragm 53 on the front plate side thereof; and apertures 51 in 75

the rear plate 48 permit the suction or pressure existing in the cleaner nozzle to reach the rear plate side of the diaphragm 53 when the signaling device 42 is in place on the suction cleaner 10, as shown in Figs. 2 and 4.

The operation of the improved suction cleaner may be described as follows:

The manufacturer of a cleaner, such as the cleaner 10, determines and establishes, in designing the same, that degree of suction or subatmospheric pressure, or in other words, the reduction from atmospheric pressure of the air existing in the cleaner nozzle 14 or other passages on the low pressure side of the fan, which is coincident with the correct adjustment of the entrance mouth of the nozzle with respect to the surface to be cleaned, whether it be a nap rug 19 or the like, or a bare floor or the like; by which adjustment a maximum or predetermined cleaning action will occur in using the particular design of cleaner with its nozzle mouth correctly adjusted.

The manufacturer, having determined that degree of suction coincident with the proper adjustment of the nozzle entrance mouth to effect a maximum predetermined cleaning action, then so designs the diaphragm 53 and button 56 of the signaling device 42 that the button will move from the position of Fig. 3 to the position of Fig. 5 the instant that a suction or pressure has been obtained in the cleaner nozzle, which is coincident with proper adjustment of the nozzle entrance mouth with respect to the surface being cleaned.

For convenience, the button 56 may have a line 62 placed thereon and the outside surface of the button to left of line 62 may be colored one color and that to the right of line 62 may be colored another color. Thus, that portion of the button to the right of line 62 cannot be seen when the button is at a position indicating proper nozzle adjustment.

Referring now to Fig. 2, assuming that the cleaner has been operated on some surface with its parts in the relative position shown in Fig. 2, which is not a correct adjustment for the particular nap rug 19 shown, and assuming that the cleaner is to be operated on nap rug 19 with proper nozzle adjustment, the sequence of attaining the proper adjustment is as follows:

The motor is running, causing fan 13 to induce an air flow into nozzle 14. The user then turns screw 38 to depress frame 36, thus depressing nozzle 14 until a position such as shown in Fig. 4 is reached, which is a proper adjustment for a nap rug 19 so as to attain a maximum predetermined amount of cleaning.

In moving from the position of Fig. 2 to the position of Fig. 4, the suction in nozzle 14 becomes increased or the pressure therein reduced to that coincident with the attainment of a maximum cleaning effect; and when that degree of suction is attained in nozzle 14, atmospheric air acts against the outside of diaphragm 43 to push the same to the right, to the position shown in Figs. 4 and 5, when button 56 indicates that the proper nozzle adjustment has been obtained. The operator upon seeing button 56 reach the position of Figs. 4 and 5, ceases to adjust the nozzle further and the cleaner may then be operated for cleaning nap rug 19.

The procedure just outlined, is taken by the operator every time the cleaner is moved to or used on a surface having different characteristics from the characteristics of the surface last

cleaned; or when the button 56 shows that an adjustment of the nozzle is required, as when the button is in any other position than that shown in Fig. 5.

Thus, each time an adjustment is made, the nozzle is raised out of sealing engagement with the surface being cleaned to a position such as shown in Fig. 2; and the nozzle is then lowered, with the fan operating, until the button moves to the position shown in Fig. 5.

In the modified form of construction shown in Figs. 8 and 9, the signaling device 42a is similar to the signaling device 42, except that the diaphragm 53a is preferably constructed of molded rubber to have a shallow cup shape with a flat peripheral edge 54a clamped between front and rear plates 43a and 48.

The molded rubber diaphragm 53a has sufficient stiffness that it substantially maintains the position shown in Fig. 8 as the suction increases in a cleaner nozzle being adjusted, until the proper adjustment is made for obtaining a maximum predetermined amount of cleaning, when the diaphragm 53a moves quickly with a snap-like action to the position shown in Fig. 9. In so moving, button 56a which is carried by diaphragm 53a moves to the position shown in Fig. 9, thus indicating the attainment of proper nozzle adjustment. The diaphragm 53a of course has sufficient resilience that it snaps back to the position of Fig. 8 whenever the nozzle is out of proper adjustment, thus indicating that fact by button 56a.

Thus, the improved signaling device may be quickly and readily attached to cleaners that are now in use by simply replacing the converter opening cover plate with a device 42 or 42a designed for the particular type of cleaner to which it is attached. Moreover, a cleaner not provided with a converter opening in a nozzle wall may be readily equipped with the improved signaling device by forming a hole in the nozzle wall of such size as will receive the improved signaling device 42 or 42a.

Moreover, in building new cleaners, the same may be equipped with the improved signaling device as shown, or one of the plates of the signaling device may be formed integrally with a nozzle wall and the signaling device constructed otherwise the same with the omission of the spring clip 49.

The present improvements as above described by way of example, thus provide a suction cleaner in which the variation in the suction or pressure of the air existing in the cleaner passage is utilized to actuate signaling means for automatically indicating to the user a desired particular suction or pressure condition of cleaning air, such as when the cleaning air has attained the proper cleaning suction by the proper adjustment of the nozzle mouth of the cleaner, to perform a maximum predetermined amount of cleaning.

Accordingly, the present improvements provide means for obtaining the objects heretofore set forth in a very simple device, which may be in the form of an attachment adapted to be secured to many existing types of cleaners to indicate proper nozzle adjustment for obtaining a maximum predetermined cleaning effect.

Having now described the features of the invention, the construction, adjustment, operation and use of preferred forms of the invention, and the advantages and results obtained thereby; the new and useful parts, elements, devices, combinations and constructions, and reasonable mechani-

cal equivalents thereof obvious to those skilled in the art, are set forth in the appended claims.

I claim:

5. 1. In a suction cleaner having walls forming a nozzle provided with a suction mouth and an auxiliary opening adapted for the reception of a converter attachment, a signal device for indicating the suction existing in the nozzle, including a plate removably secured to said nozzle wall and covering said opening, and a nozzle suction operated indicator mounted on the plate communicating through said plate with the suction nozzle.
10. 2. In a suction cleaner having a fan, walls forming a suction passage on the suction side of the fan, there being an opening in one of said walls, and suction operated nozzle suction indicating means removably secured to said wall over said opening.
15. 3. In a suction cleaner having walls forming a nozzle, one of said nozzle walls having spaced wall parts forming a compartment, one of said wall parts having means providing communication between the compartment and the interior 20 of the nozzle and the other wall part having means providing communication between the compartment and the atmosphere, a diaphragm in said compartment between said wall parts, and a signaling indicator button connected to said 25 diaphragm and extending through said last mentioned wall part.

4. An attachment for a suction cleaner including spaced wall parts forming a compartment, there being a plurality of openings through one of said wall parts, a diaphragm in said compartment, an indicator mounted on and carried by 5 said diaphragm and extending through one of said openings, and a spring attaching clip carried by the other wall part for removably securing the attachment to a suction cleaner to cover an opening in the nozzle thereof.

5. An attachment for a suction cleaner including inner and outer wall parts having spaced portions forming a compartment, there being openings through said wall parts, a diaphragm in said compartment having its peripheral edge clamped 10 between said wall parts, a visible indicator mounted on and carried by said diaphragm and extending through the opening in the outer wall part, a spring reacting between the indicator and inner 15 wall part, and securing means on the attachment 20 for removably securing the attachment to a cleaner to cover the converter opening thereof.

6. In a suction cleaner having a fan, walls forming a suction passage on the suction side of the fan, there being an opening in one of said 25 walls, and resilient suction operated nozzle suction indicating means removably secured to said wall over said opening.

EUGENE F. MARTINET. 30
